CLAIM

The ornamental design for a fluid block, as shown and described.

DESCRIPTION

FIG. 1 is a front view of a fluid block showing our new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a section view along the line 7-7 from FIG. 5;

FIG. 8 is a front, plane, perspective view from the right side thereof;

FIG. 9 is a front, plane, perspective view from the left side thereof;

FIG. 10 is a perspective view from the bottom, back, and right side thereof;

FIG. 11 is a perspective view from the bottom, back, left side thereof; and,

FIG. 12 is a reference diagram thereof.

The article relating to the design of the present application is a fluid block that forms a flow path that can be connected between fluid devices such as flow meters and valves so that fluid can flow without leakage. The fluid block is connected to other blocks by engaging the convex part on the right side and the concave part on the left side.
